Attorney.

UNITED STATES PATENT OFFICE.

FREDERIC K. PLUMBLY, OF BUFFALO, NEW YORK, ASSIGNOR TO THE BUFFALO STEEL HOUSE COMPANY, OF SAME PLACE.

GARBAGE AND EXCREMENT CREMATORY.

SPECIFICATION forming part of Letters Patent No. 567,506, dated September 8, 1896.

Application filed August 31, 1894. Renewed August 5, 1896. Serial No. 601,802. (No model.)

To all whom it may concern:

Be it known that I, FREDERIC K. PLUMBLY, a citizen of the United States, residing at Buffalo, in the county of Erie and State of New York, have invented certain new and useful Improvements in Garbage and Excrement Crematories; and I do hereby declare the following to be a full, clear, and exact description of the invention, such as will enable others skilled in the art to which it appertains to make and use the same, reference being had to the accompanying drawings, and to figures of reference marked thereon, which form a part of this specification.

The object of my invention is to provide means of a portable character for the disposal of garbage and excrement by cremation, the same being adapted for use in private and boarding houses, hotels, factories, public parks, or other places which have no sewer connections, the idea being to effect the disposal of the garbage or excrement at the points of accumulation, in a quick and efficacious manner and without the presence of offensive odors, thus dispensing with the costly and disagreeable handling of the same consequent upon its transportation through the streets of a city.

To this end my invention consists of a metallic casing having in its lower portion a fire-box and ash-pit. An iron pot or receptacle is hung by trunnions seated in the side walls of the casing, leaving an upper space between it and the top of the casing. A draft-passage between this upper space and the fire-box surrounds the pot or receptacle, being connected at one side by separate openings with the upper space and the fire-box and at the other side with the smoke-pipe leading to the chimney. The foul air from the decomposing or burning matter in the upper space is drawn down through its separate opening into the draft-passage and the products of combustion from the fire-box are drawn up through its separate opening into the same draft-passage, meeting and mingling therein with the foul air from above and conducted through the common draft-passage to the smoke-pipe. The cover of the casing is to be suitably constructed for either of its uses, as a garbage receptacle or a closet.

I will now proceed to minutely describe the manner in which I have carried out my invention and then claim what I believe to be novel.

In the drawings, Figure 1 is a side elevation of my invention. Fig. 2 is a vertical section taken in the line *x x* of Fig. 1. Fig. 3 is a horizontal section taken in the line *yy* of Fig. 2. Fig. 4 is a similar section taken in the line *y' y'* with the pot removed. Fig. 5 is a vertical section taken in the line *zz* of Fig. 2 with the pot removed. Fig. 6 is a side elevation, partly in vertical longitudinal section; and Fig. 7 is a vertical transverse section of a modified form of pot or receptacle.

Referring to the drawings, 1 is a metallic casing, preferably of cylindrical configuration. In the bottom of the casing is the ash-pit 2, having the door 3. Above the ash-pit 2 is the fire-box 4 with sloping side walls and grate-bars 5, and 6 6 are the doors leading therein.

7 is a partition extending over the top of the fire-box, having the central opening 8 and the side concentric opening or passage 9.

10 is a pot or receptacle provided with side trunnions 11 12, resting loosely in sockets in the circular ledge 13 and provided with the crank 14 for turning it to dump its contents.

15 is a concentric passage opening downwardly from the upper space 16 into the draft-passage 17, formed by the partition 7 above the fire-box and the ledge 13 and pot or receptacle 10, which passes down centrally through this draft-passage, its bottom resting, when in position, in the opening 8 of the partition 7. A curved partition or deflector 18 is secured to the side wall of the casing 1 midway between the opening 9 in the partition 7 and the passage 15 just above it. The inner edge 19 of the deflector 18 rests against the outside wall of the pot or receptacle 10, and this deflector serves as a partition between the passage 15 from the upper space 16 into the draft-passage and the opening 9 in the partition 7 from the fire-box 4 into the same draft-passage 17, directing both the cold air from above and the smoke from below horizontally into this passage. A flue 20, opening into the smoke-pipe 21, is preferably provided with the damper 29, opening

into the draft-passage 17, and the damper 22, opening into the upper space 16, which has the openings 23 through its side wall.

24 is a removable cover fitting over the top 5 of the casing 1 and provided with a central opening 25, through which garbage may be dropped into the pot or receptacle 10.

When the casing is used as a closet, a proper seat with hinged cover may be substituted 10 for the cover 24.

The device just described operates as follows: The lid 26 (shown in dotted lines) being removed the garbage is dropped into the pot 10 and the lid replaced. The intense heat 15 generated in the fire-box coming in direct contact with the bottom of the pot 10 and passing up through opening 9 in the partition 7 against the deflector 18 and in contact with the side walls of the pot as it passes 20 around the same through the draft-passage 17 to the smoke-pipe serves to first dry and then incinerate the garbage. The air forming the draft through the upper space 16 is drawn in through the openings 23 and is 25 drawn down through the passage 15 against the deflector 18 and into the draft-passage 17, where it commingles with the products of combustion from the fire-box and passes out through the smoke-pipe, the valve 29, if used, 30 regulating its passage and hence the speed of consumption. In its passage as just described it carries with it first the offensive gases from the drying garbage and later the other gases generated by the cremation of 35 the garbage. The valve 22, if used, may be partially opened to permit unconsumed gases passing from the draft-passage 17 to return to the upper space 16, commingle with the incoming fresh air, and pass again around 40 the pot. In this manner the garbage is completely consumed without the escape of any offensive odors even should the lid be removed during the cremation. After the garbage is completely incinerated the pot can 45 be tipped up and the contained ashes dumped upon the fire below through the opening 8 in the partition 7. In case the device is employed as a closet, as it may be in buildings having no sewer connections, a proper cover 50 is removably placed upon the casing with an opening, and the pot or receptacle 10 catches the excrement, which can be cremated in the same manner as the garbage, it being impossible for any offensive odors to escape either 55 before or during the cremation.

My improved crematory just described can be made in different sizes to meet the varied requirements as to the quantity of garbage to be consumed.

60 Instead of entirely consuming the garbage in the pot 10, it can, when thoroughly dried, be dumped into the fire-box and used as fuel, in which event a considerable saving is effected.

65 The garbage being thus cremated in an inoffensive manner upon the premises the expense and trouble of its removal as now prac-

ticed in cities are entirely eliminated, together with all danger from sickness caused by the poisonous gases generated from its 70 decomposition.

In Figs. 6 and 7 I have shown a modified form of pot or receptacle 27, provided with a flue or passage 28, extending through the same in the direction of the draft and open at both 75 ends. This serves to increase the heating-surface and thus facilitates the incineration of the garbage. The casing with its pot or receptacle may, if desired, be elongated and the cover provided with a series of closet-seats, the one pot or receptacle catching the excrement to be cremated from the different seats.

I claim—

1. The herein-described garbage or excrement crematory, the same consisting of an outer casing, two transverse partitions dividing the casing into three chambers the lowest of which is a combustion-chamber, said partitions being provided with openings near 90 their centers, a pot removably closing said openings and leaving a passage around it within the central chamber, said partitions being also provided with openings near one side of the casing producing communication 95 between the several chambers, the upper chamber being provided with air-inlet openings and the central chamber with an outlet-opening for the products of combustion, and an exit-flue communicating with the latter 100 opening, as and for the purpose set forth.

2. The herein-described garbage or excrement crematory, the same consisting of an outer casing, two transverse partitions dividing the casing into three chambers the lowest of which is a combustion-chamber, said partitions being provided with openings near 105 their centers, a hemispherical pot hung on trunnions in the upper partition and closing the opening therein and that in the lower 110 partition, one of the trunnions having a crank-handle outside the casing, said partitions being also provided with openings near one side of the casing producing communication 115 between the several chambers, the upper chamber being provided with air-inlet openings and the central chamber with an outlet-opening for the products of combustion, and an exit-flue communicating with the latter 120 opening, as and for the purpose set forth.

3. The herein-described garbage or excrement crematory, the same consisting of an outer casing, two transverse partitions dividing the casing into three chambers the lowest 125 of which is a combustion-chamber, said partitions being provided with openings near their centers, a pot removably closing said openings and leaving a passage around it within the central chamber, said partitions being also provided with openings near one side of the casing producing communication 130 between the several chambers, a deflector extending from the casing to the side of the

pot and standing between these side openings in the two partitions, the upper chamber being provided with air-inlet openings and the central chamber with an outlet-opening for the products of combustion, and an exit-flue communicating with the latter opening, as and for the purpose set forth.

4. The herein-described garbage or excrement crematory, the same consisting of an outer casing, two transverse partitions dividing the casing into three chambers the lowest of which is a combustion-chamber, said partitions being provided with openings near their centers, a hemispherical pot hung on trunnions in the upper partition and closing the opening therein and that in the lower partition, one of the trunnions having a crank-handle outside the casing, said partitions being also provided with openings near one side of the casing producing communication between the several chambers, a deflector extending from the casing to the side of the pot and standing between these side openings in the two partitions, the upper chamber being provided with air-inlet openings and the central chamber with an outlet-opening for the products of combustion, and an exit-flue communicating with the latter opening, as and for the purpose set forth.

5. The herein-described garbage or excrement crematory, the same consisting of an outer casing, two transverse partitions dividing the casing into three chambers the lowest of which is a combustion-chamber, said partitions being provided with openings near their centers, a pot removably closing said openings and leaving a passage around it within the central chamber, said partitions being also provided with openings near one side of the casing producing communication between the several chambers, the upper chamber being provided with air-inlet openings and the central chamber with an outlet-opening for the products of combustion, an exit-flue communicating with the latter opening and extending thence upward to a chimney, a damper controlling this opening, a return-opening between the flue and the upper chamber, and a damper controlling this opening, as and for the purpose set forth.

In testimony whereof I have signed my name to this specification in the presence of two subscribing witnesses.

FREDERIC K. PLUMBLY.
